DARRELL F. DYKE, OF LOS ANGELES, CALIFORNIA, ASSIGNOR TO KROEHLER MFG. CO.,
OF NAPERVILLE, ILLINOIS, A CORPORATION OF ILLINOIS

FOLDING LEG

Application filed July 9, 1925, Serial No. 42,375. Renewed December 30, 1929.

This invention relates particularly to a folding leg construction for davenport beds but of course may have a more general use wherever applicable. The principal object 5 of the invention is to provide a supporting leg structure of this kind which may be attached at the ends of a moving or foldable seat frame in such a manner that the leg will be folded within the space defined by the ends 10 of the seat frame before the seat frame itself is folded within the davenport frame. A further object is to brace the foldable leg in its extended position. Further objects will appear hereinafter.

15 In the drawings, Fig. 1 is a side elevation of a folding seat structure to which the leg comprising this invention is attached; Fig. 2 is a sectional plan of the parts shown in Fig. 1; Fig. 3 is an enlarged outer view of 20 a leg in extended position; Fig. 4 is a section taken on the line 4—4 of Fig. 3; Fig. 5 illustrates the leg in closed position; and Fig. 6 is a section taken on the line 6—6 of Fig. 5, showing the leg in closed position.

25 In the folding leg commonly employed in davenport beds, the leg projects beyond the end of the seat frame so that it is necessary to leave an objectionable space between the seat frame and the end frame of the davenport in order to fold the leg therein without 30 undue contact with the inner side of the davenport end frame. The present invention overcomes this objection by providing a pivoted and sliding leg mounted at the end 35 of the seat frame in such a manner that the outer face of the leg is flush with the end of the seat frame or is actually within the confines of the end of the seat frame so that there is no danger of the leg scratching the end 40 frame of the davenport or coming in contact with it in folding and unfolding the seat frame and the folding bed structure of a davenport bed.

45 Referring more particularly to the drawings, a davenport bed end is represented by numeral 1 in which is foldable an articular metal bed frame 2, the particular construction of which is immaterial for the purposes of this invention; the bed davenport comprises a frame 3 for an upholstered seat which

is invertible in front of the davenport frame upon a hinge construction mounted behind a front board 4 of the davenport frame upon a hinge construction pivoted in a plate 5 secured to the davenport frame. The hinge 55 comprises a plurality of pivotal connected links 4, 5, 6 and 7 connected to each other to the plate 5 and to a seat bracket 8, the hinge construction also supporting the inner side of the seat frame 3 when in its inverted position. 60

The folding leg construction comprises a plate 9 adapted to be secured by one edge to the inside of the seat frame 3 and having an offset 10 therein which rests upon the upper edge of the seat frame in its inverted position, the ledge formed by the offset being graduated in width from front to back, as shown more clearly in Fig. 2. The extending portion of the plate is formed with slots 11 and 12 each having a straight part for a portion of its length and an irregular or curved portion at the inner end thereof. A leg 13 has headed projections 14 and 15 secured thereto and slidable in the slots 11 and 12, and immediately below the portion to which the headed rivets or projections are attached is an offset 16 which extends the lower portion of the leg over the adjacent outer edge of the seat frame 3, as shown more clearly in Fig. 4.

70 On the inner side of the leg is another headed projection 17 which is adapted to be engaged in a central recess 18 of a substantially semicircular metal bracket plate 19 attached to the outer side of the seat frame 3 75 in a position to engage the projection 17.

75 Connecting the leg 13 and one of the hinge links 4 is a leg operating link 20 which may be secured to the leg by means of the headed projections 14.

80 In operation the opening of the davenport bed by overturning the seat causes a longitudinal movement of the headed projections 14 and 15 of the folding leg 13 in their respective slots 11 and 12 and when the seat is almost reached the limit of its overturning movement, the irregular portions of the slots 11 and 12 cause a swinging movement of the leg into supporting position. At this time the headed projection 17 engages the recess 95 100

of the supporting plate 19 and the leg is held firmly in its position. In order to fold the leg the seat frame is raised which operates the link 20 because of its differential relation to the hinge links, and the leg is first disengaged from the plate 19, then rotated at right angles to its supporting position with respect to the frame, and then moved longitudinally parallel with the frame until it assumes the folded position as shown in Figs. 5 and 6. As the plate 9 is inclined toward the outer end of the seat frame 3, its closing movement will cause the leg to be drawn in so that its outer surface is flush with the outer end of the seat frame 3, or it may even be within the confines of this end of the seat frame.

With this construction it is apparent that the leg will be folded and unfolded automatically and there will be no danger of the leg engaging the end frame of a davenport to prevent the folding and unfolding operation of the seat frame, nor will there be any danger of the leg construction engaging and scratching or tearing the construction of the davenport end frames.

I claim:

1. The combination with a movable seat frame, of a folding leg structure attached to the frame including a slotted plate inclined to the end of the frame, and a leg having projections engaged by the slots of the plate and thereby guided from a position within the confines of the frame as the seat frame is moved to an extending position projecting from the edge of the frame for supporting the frame in open position, and means to move the leg relatively to the plate as the seat frame is moved.

2. A davenport bed having a seat frame invertible from a position within the davenport frame to an extended position in front thereof, hinge mechanism for mounting the seat in the frame, and a folding leg structure mounted on the under side of the seat frame including a slotted plate inclined to the plane of the end of the seat, the leg having means movably connecting it to the slots in the plate, and means operatively connecting it to the hinge mechanism whereby the movement of the seat will move the leg relative to the plate to project the leg from a position within the edge of the seat frame to a position overlying the edge of the seat frame for supporting it in open position.

3. The combination with a davenport frame, of a seat frame movable therein, hinge mechanism upon which the seat frame is mounted in the other frame, a folding leg structure attached to the under side of the seat frame and including a slotted plate inclined to the end of the seat frame, the leg having means forming a connection with the hinge mechanism and having means movably engaging the slots in the plate and movable from a position parallel to and below the un-

der side of the seat to a position at right angles thereto extending over the edge of the seat for supporting it in open position, and means for moving the leg relative to the plate.

4. A folding leg structure comprising a plate with slots therein, a portion of the slots being parallel and adjacent ends having irregular portions, a leg member having projections slideable in the slots and means for moving the leg with respect to the slots whereby it is turned by the irregular portion of the slots to a position at right angles from that which it occupies when the projections are in engagement with the parallel portions of the slots.

5. A leg construction comprising a plate having slots and adapted to be set at an angle at the edge of a frame which the leg is to support, a leg member having projections to guide it in the slots of the plate, the slots having parallel and irregular portions and the movement of the projections in the slots turning the leg substantially at right angles and projecting it laterally according to the incline of the plate and means to move the leg member relative to the plate.

6. The combination with a seat frame, of a supporting leg structure therefor, the leg structure comprising a plate attached to the inner edge of the seat frame having slots therein and extending at an angle with respect to the edge but within the end of the seat frame, a leg member having projections engaging in the slots and guided thereby from a position parallel with the edge of the seat frame and within the plane of the outer edge thereof to a position at right angles thereto and projecting across the edge of the seat frame and means for moving the leg member relative to the plate.

7. The combination with a movable frame, of a supporting leg therefor comprising a movable leg member and means for mounting the leg to move from a position parallel to and within the edge of the frame to a position at right angles thereto and extending across the edge of the frame, and a bracket attached to the end of the frame having a recess therein, the leg member having a projection adapted to hook into the recess of the bracket when the leg is in its extended position for holding it more securely in place, and unhook therefrom by the reverse movement of the leg.
